UNITED STATES PATENT OFFICE.

ANTHONY J. SENGER, OF SANTA ANA, CALIFORNIA.

SPEED-CHANGING GEAR.

1,177,282.

Specification of Letters Patent. Patented Mar. 28, 1916.

Application filed April 8, 1915. Serial No. 19,865.

To all whom it may concern:

Be it known that I, ANTHONY J. SENGER, a citizen of the United States, residing at Santa Ana, in the county of Orange and State of California, have invented certain new and useful Improvements in Speed-Changing Gear, of which the following is a specification.

This invention relates to an improvement in change speed gear mechanism for motor driven vehicles, and more specifically pertains to the form known as the direct driven type.

One of the objects of the present invention is the provision of longitudinally slideable gears mounted upon the rear axle, and adapted to be moved predetermined distances for proper engagement with different speed pinions which are provided with suitable clutches for connecting with the engine shaft.

A further and important object of this invention is to provide a plurality of sliding boxes, each containing a speed pinion of different size, namely, first, second, third and reverse speeds, said pinions designed to engage with gears on the rear axle for imparting motion to the vehicle.

Still another object is to provide a mechanism of this character which is simple in construction, easy to operate and positive in its operation.

With these and other objects and advantages in view, the invention consists in the preferred construction and arrangement of parts which will be more fully hereinafter described and claimed and subject to such variations as fairly fall within the scope of the claims.

In said drawings, Figure 1 is a longitudinal section of the invention as applied to an automobile; Fig. 2 is a horizontal section taken on the line 2—2 of Fig. 3; Fig. 3 is a vertical longitudinal section of the invention showing the sliding box construction and its operating means; Fig. 4 is a front elevation of the female clutch members; Fig. 5 is a plan view of the rack and pinion mechanism for sliding the gears; and Figs. 6 and 7 are horizontal and vertical longitudinal sections respectively of a modified form of the invention.

Referring to the drawings and more particularly to Figs. 1 to 4 thereof, the numeral 10 indicates a housing or casing for the entire mechanism, comprising side members

11 and 12, end members 13 and 14, and suitable top and bottom members not shown. This housing contains a suitable lubricant for the mechanism, and the side members 60 11 and 12 thereof are provided with openings through which the axle 17 extends. This axle is provided with the usual form of differential gears (not shown).

18 indicates a tubular casing surrounding the axle and differential gears, and rigidly connected to the axle by means of a key 19. Said casing 18 is provided throughout its entire length with an exteriorly longitudinally extending groove 20, the purpose of which will be described hereinafter. Surrounding the casing 18, and longitudinally slideable thereon is a sleeve 21 upon which are rigidly mounted gears 22, 23, 24 and 25. This sleeve 21 is provided with a key 26 adapted to loosely engage with the groove 20, thereby allowing the sleeve to freely move longitudinally with respect to the casing 18, but preventing any rotary motion thereof upon said casing 18. 70 75 80

Rigidly secured to and longitudinally slideable with the sleeve 21, is a frame indicated as a whole by the numeral 21', comprising side members 27 and 28, and a cross bar 29 attached at each end to the rear edges 85 of side members 27 and 28. Extending longitudinally across the front of the frame is a rack bar 30 which is secured to the side members 27 and 28 by any suitable means, the purpose of said bar will be described 90 hereinafter.

To the front edge of the frame 21', is secured a member 31, the purpose of which is to support a series of sliding boxes 32, 33, 34 and 35. 95

36 and 37 indicate two stationary longitudinally disposed cross bars extending above and below respectively of the member 31, and each provided throughout its length with longitudinal grooves 38 and 39, and having transverse grooves 40 and 41 intermediate their ends, said transverse grooves extending approximately one-half of the width thereof. 100

To one end of each of the sliding boxes 32, 33, 34 and 35, are attached plates 42, 43, 44 and 45 the upper and lower extremities of which extend above and below the sliding boxes, and are adapted to project into the grooves 38 and 39 so as to allow the sliding 110 boxes to move longitudinally, but prevent any transverse movement. Each of these

sliding boxes 32, 33, 34 and 35, carries a shaft 46, 47, 48, 49, respectively, which is provided on one end thereof with a different speed pinion 50, 51, 52, 53 representing 1st, 5 2nd, 3rd and reverse speeds respectively, which are adapted to engage with the gears 22, 23, 24, 25, and on the opposite end is formed female clutch members 54, 55, 56, 57. 58 represents the drive shaft from the 10 engine extending through the front end wall 14 of the frame, and provided with a squared off portion 59 on its end upon which is slidably mounted a collar 60. This collar 60 is formed integrally with a male clutch 15 member 61 and is connected thereto by a sleeve 62. Vertically extending from the top and bottom of said collar 60, are pins 63 which are adapted to connect the collar with a clutch operating member 64, the purpose of which is to withdraw the clutch 61 from engagement with either of the clutches 54, 55, 56 and 57 when desired. One end of the member 64 is pivoted at 65 to the front 20 portion 14 of the frame and to the other end thereof is connected one end of a lever 66 which extends toward the front of the vehicle and at its forward extremity is connected with a foot lever 66'. Interposed between the member 64 and the front portion 25 14 of the frame, is a spring 67 adapted to normally hold the clutch 61 in engagement with one of the clutches 54, 55, 56 and 57 when expanded and designed to disconnect the said clutches when contracted. 30 68 indicates a member, transversely slidable with respect to the member 31, for engaging and disengaging the pinions 50, 51, 52, 53 with the gears 22, 23, 24, 25. This device comprises a frame portion 69 extending through an opening 70 provided in the member 64 and a portion 71 rigidly connected with said portion 69. Each of the portions 69 and 71 is constructed from a single piece of metal and comprise U-shaped frames which are rigidly united together by means of a spot welded joint 72. The portion 69 of this device is slidably mounted on the squared off portion 59 of the shaft 58, and the end plate 73 thereof is adapted to 40 form a stop for the slidable collar 60, a spring 74 being interposed between the plate 73 and the front member 14 of the casting 10 for the purpose of cushioning the said device 68. 45 50 The portion 71 of the member 68 is provided with longitudinally extending channels or grooves 75 designed to register, when the member 68 is in its inoperative position, with the grooves 38 and 39 in the cross bars 36 and 37, and, when in its operative position, adapted to slide into the transverse grooves 40, 41 in said cross bars 36 and 37. In operation, these grooves 75 are 55 designed to receive the projecting ends of 60 the plates 42, 43, 44, 45 attached to the sliding boxes 32, 33, 34, 35, and allow said sliding boxes to move transversely backward and forward, thereby causing the pinions 50, 51, 52, 53 to engage and disengage with the gears 22, 23, 24, 25. This portion 71 is 70 also provided adjacent to said grooves 75 with longitudinally disposed flanges 77 and 78 adapted to contact with and slide upon the top and bottom portion of the member 31 for the purpose of maintaining the member 68 in a true horizontal position so that the grooves 75 in said portion 71 will always properly register with the grooves 38 and 39 in the cross bars 36 and 37. 75 The foot lever 66', to which is connected one end of the clutch operating lever 66, is pivoted to a brace 79 depending from the bottom of the vehicle frame, and said lever 66' is connected by suitable leverage 80 to the ordinary clutch 81 which connects the drive shaft 58 with the engine 82. It will be understood that upon exerting pressure upon this foot lever 66' the clutch 81 by means of the leverage 80 will disconnect the shaft 58 from the engine 82, and will also withdraw the clutch 61 from engagement with the clutch 56 through the medium of the clutch operating member 64, whereby the shaft 58 will be free from any power from the engine, and the gear shifting may 90 take place without danger of injuring, or stripping the teeth of the gears. It will also be readily seen that upon removing the pressure from the lever 66' the clutch 81 will be thrown in to connect the drive shaft 58 with the engine 82, the clutches 61 and 56 will engage with each other, and by means of the pinions 50, 51, 52, 53 and the gears 22, 23, 24, 25, motion will be imparted to the 95 vehicle. 100 83 indicates a slot in the floor of the vehicle through which the lever 66' is designed to extend and reciprocate, said slot being provided with a notch 84 into which the lever 66' is adapted to be engaged for the purpose of holding the clutches in inoperative position. 105 85 represents a longitudinally extending shaft to one end of which is secured a pinion 86 meshing with the rack 30 and to the other end thereof is fastened a beveled gear 87 meshing with teeth on a half moon quadrant 88. This shaft is supported in brackets 89, 90 which are fastened to the floor of the vehicle, and to the top of the cross bar 36 respectively. The quadrant 88 is rigidly secured to the lower extremity of a gear shifting lever 91 which is provided with a usual form of spring catch 92, adapted to engage with notches 93 on a quadrant 94 110 fastened by suitable means to the frame of the vehicle. These notches 93 indicate the position of the lever for the different speeds, namely, first, second, third and reverse speeds. 115 120 125 130

In operation, assuming that the foot lever 52 is engaged in the notch 84, it will be readily understood that none of the operating parts are connected. To impart motion to the vehicle, the lever 91 is first moved adjacent to the proper notch marked 1, indicating the first speed, such movement through the operation of the quadrant 88, gear 87, shaft 85 and pinion 86 will slide the frame 21 which carries the gears 22, 23, 24, 25, and the member 31 containing the sliding boxes 32, 33, 34, 35 in which are mounted the pinions 50, 51, 52, 53 and the clutches 54, 55, 56, 57, the proper distance so as to bring the clutch member 54 in alignment for engagement with the clutch member 61. This being done, the foot lever 52 is then released from engagement with the notch 84, and through the action of the spring 67, the clutches 54 and 61 are connected together. Furthermore, after the clutches 54 and 61 have been connected, this spring 67 serves to force the member 68 into the transverse slots 40 and 41, carrying therewith the sliding box 32 and the first speed pinion 50 mounted therein, whereby said first speed pinion 50 will mesh with the gear 22 on the rear axle, and thereby impart motion to the vehicle. The operation just described is adapted to start the vehicle on first speed, and to change the speed to second and further to third or to reverse the movement of the vehicle, this operation is repeated, except it is not necessary to engage the lever 66 in the notch when changing speeds as the notch is for the purpose of holding the clutches out of engagement so that the engine may run while the vehicle is standing still.

In Figs. 6 and 7 is shown a modified form of the present invention which operates similar to the before described construction. In said figures, 95 indicates a casing for the mechanism. Supported by roller bearings 96 and 97 in said casing 95 are two half axles 98 and 99 which are connected with a usual form of differential gear 100. 101 indicates a housing for this differential gear 100, and is rotated therewith by means of its connection with gears 102, 103 of said differential gear. Suitably keyed to, and longitudinally slidably upon this housing 101, are provided gears 104 and 105, the first named representing the forward speed gear and the latter mentioned the reverse speed gear respectively. These gears 104 and 105 are normally held in their inoperative position by means of springs 106 and 107 which encircle the housing 101. Integrally formed on the rear surface of each of these gears 104 and 105, are lugs 108 and 109 which are provided with inclined faces 110 and 111, and adjacent to said lugs 108 and 109, keys 112 and 113 are provided. Each of these keys 112 and 113 is provided with an inclined

face 114 and 115 which corresponds to the degree of inclination of the faces 110 and 111 of the lugs 108 and 109, and to each of said keys 112 and 113 are attached levers 116 and 117 for operating said lugs. Slidably mounted in the casing 95, are a series of sliding boxes 118, 119 and 120 which contain shafts 121, 122 and 123, to one end of which are secured speed pinions 124, 125, and 126 and to the other extremities are attached female clutch members 127, 128 and 129. 130 indicates a rack which is engaged by a pinion 131, adapted to be operated by suitable mechanism as shown by numerals 85, 87 and 88 in Figs. 1 and 3 for sliding the boxes 118, 119 and 120 to the desired position so that the gears 104 and 105 and pinions 124, 125 and 126 may mesh, and also to connect the clutches 127, 128 and 129 with a male clutch 132, which is slidably mounted on the drive shaft 133. Pivoted at 134 to the casing 95, is a clutch operating lever 135, which is swiveled at 136 to the clutch member 132. To this lever 135 is connected a rod 135' which extends to the forward end of the car and is attached to a foot lever similar to that shown at 66' in Fig. 1, and is adapted to disconnect either of the clutches 127, 128 and 129 from engagement with the clutch member 132 when so desired. A spring 141 is interposed between the lever 135 and the casing 95 for the purpose of forcing said pinions 124, 125 and 126 into engagement with the gears 104 and 105.

For the purpose of returning the pinions 121, 122 and 123 to their normal or inoperative position, after being engaged with the gears 104 and 105, a spring 137 is provided, one being employed for each of the sliding boxes 118, 119 and 120. This spring is fastened at 138 to one end of the sliding box, and at its other end is attached to a lug 139 projecting from the casing 95, which lug is adapted to engage in a slot 140 formed in the sliding boxes, thereby allowing said sliding boxes to reciprocate.

In operation when it is desired to start the vehicle at first speed rate the lever 116 is first operated to exert a pulling effect on the key 112 and thereby, owing to the inclined faces 110 and 114 of the lug 108 and key 112 respectively, force the gear 104 into operative position. This being done, the sliding boxes carrying the pinions 124, 125 and 126 are operated by means of the rack 130 and pinion 131 so as to bring the pinion 124 into operating position, when the clutch member 135 is actuated to connect the clutches 127 and 132 and by means of the spring 141 the pinion 124 is forced into engagement with the gear 104 whereby the car is started. To change the speed of the car to second, third or reverse the motion of the car, this operation is repeated.

I claim:

1. In a change speed gear mechanism, the combination of gears mounted to slide on the rear axle of a vehicle, means for sliding said gears, a drive shaft, a clutch mounted on said drive shaft, and means, comprising a plurality of sliding boxes each containing a speed pinion, a shaft, and a clutch member, for connecting said drive shaft with said gears.
2. In a change speed gear mechanism, the combination of gears slidably mounted on the axle of a vehicle, means comprising a rack and pinion for sliding said gears, a drive shaft provided with a squared off portion, a clutch slidably mounted on said squared off portion, means for operating said clutch, a series of sliding boxes interposed between said clutch and the gears on the axle for connecting the same, each of said sliding boxes carrying a shaft having a pinion formed on one of its ends for engagement with said gears, and a clutch member formed on its other end for connecting with said clutch on the drive shaft, means for supporting said sliding boxes, and means for operating said sliding boxes.
3. In a change speed gear mechanism, the combination of a series of gears mounted on a sleeve slidably mounted on the axle of a vehicle, a frame attached to said sleeve and slide therewith, a second frame attached to the forward edge of said first mentioned frame for supporting a series of sliding boxes, each carrying a speed pinion adapted to engage with said gears, a shaft, and a clutch member, cross-bars arranged above and below the second named frame respectively, said cross bars being provided with longitudinal and transverse grooves, a drive shaft, a clutch slidably mounted on said drive shaft and designed to engage with the clutch member carried by said sliding boxes, and means, for operating the sliding boxes and engaging in said grooves in said cross-bars, for connecting the drive shaft with the gears.
4. In a change speed gear mechanism, the combination of a series of gears mounted on a sleeve slidably mounted on the axle of a vehicle, a frame attached to said sleeve and slide therewith, a second frame attached to the forward edge of said first mentioned frame for supporting a series of sliding boxes, each carrying a speed pinion adapted to engage with said gears, a shaft, and a

clutch member, cross-bars arranged above and below the second named frame respectively, said cross-bars being provided with longitudinal and transverse grooves, a drive shaft, a clutch slidably mounted on said drive shaft and designed to engage with the clutch member carried by said sliding boxes, and means, for operating the sliding boxes and engaging in said grooves in said cross-bars, for connecting the drive shaft with the gears, said means comprising a plurality of U-shaped members rigidly fastened together, one portion thereof being provided with an opening for the reception of a clutch operating device, and the other portion being formed with channels adapted to receive a plate on the end of one of the sliding boxes for operating the same.

5. In a change speed gear mechanism, a drive shaft, a driven shaft, gears slidably mounted on said driven shaft, means interposed between said drive shaft and said gears for connecting the same, and means for sliding said gears, said means comprising a rack adapted to slide the gears, a shaft provided on one end with a pinion designed to operate said rack, and on the other end provided with a gear adapted to be operated by a lever carrying a half moon segment.

6. In a change speed gear mechanism, a drive shaft, a clutch member slideable thereon, a driven shaft, means comprising a series of sliding boxes for connecting the drive shaft and driven shaft, each of said sliding boxes being provided with a plate on one end thereof, and means engaging said plate, and connecting with said clutch, for simultaneously operating said clutch and said sliding boxes.

7. In a change speed gear mechanism, a drive shaft, a driven shaft, sliding boxes interposed therebetween for connecting the same, means for operating said sliding boxes, a clutch slidably mounted on said drive shaft, a collar integrally formed therewith, and pins extending from said collar and through openings provided in the sliding box operating means, for connecting with a clutch operating means.

In testimony whereof I affix my signature in presence of two witnesses.

ANTHONY J. SENGER.
